UNITED STATES PATENT OFFICE.

MARTAIN L. TOLBERT, OF ELDON, IOWA.

RIDING-SADDLE.

SPECIFICATION forming part of Letters Patent No. 283,043, dated August 14, 1883.

Application filed April 30, 1883. (No model.)

To all whom it may concern:

Be it known that I, MARTAIN L. TOLBERT, a citizen of the United States, residing at ELDON, in the county of Wapello and State of Iowa, have invented a new and useful Spring-Saddle, of which the following is a specification, reference being had to the accompanying drawings.

This invention relates to saddles provided with springs to render the same of greater comfort to the rider; and it consists in certain improvements in the construction and combination of parts, as hereinafter particularly set forth.

15 In the accompanying drawings, Figure 1 is a side view of a saddle embodying my improvements. Fig. 2 is a vertical longitudinal section of the same. Fig. 3 is a plan view, a portion of the top plate being broken away. 20 Fig. 4 is a detail view of the plate carrying the springs.

The same letters refer to corresponding parts in all the figures.

Referring to the drawings, A designates the 25 pommel, B the cantle, and C the saddle-tree proper, showing my spring attachment in position. In the upper face of the cantle is formed a groove or recess, b, extending around parallel with the circumference of the said 30 cantle, and in said recess is fitted or secured a plate, D, of the exact conformation of the recess. This plate is provided with pins or studs d, arranged at suitable intervals around the same, and over said pins or studs are fitted 35 a corresponding number of coiled, spiral, or flat springs, e, arranged to have free and loose play thereon. A plate, E, is placed over the pins and springs, and is secured to the cantle in any suitable manner.

40 In the upper face of the cantle additional pins and springs may be added to secure further elasticity of the saddle. In that case the pins will simply project from the face of the cantle without using a bottom plate.

45 The operation of my spring-saddle is obvious. While the saddle is being used the weight of the rider will depress the top plate against the tension of the springs, and thus the springs will form a soft, elastic, cushion-like seat, 50 which will prove of inestimable value in horse-back-riding.

The top plate can be covered with leather of the kind adapted to this branch of harness, and any sort of spring may be substituted for that shown.

55

My improved spring attachment can be applied to any of the well-known saddles in use.

As shown, an inner plate, F, may be fitted in a groove or recess, f, of the cantle, within the groove b. Pins or studs and springs are 60 attached to said plate and form an additional elastic means for the saddle.

It is obvious that various modifications can be made in the construction of the same without departing from the spirit or scope of my 65 invention.

The principal advantage of my spring-saddle is, that by its use equestrians are not subjected to the jar and jolt of horseback-riding. The riding is very easy, and the usual discomforts are obviated by my elastic cushion-like saddle.

70

My saddle is simple, durable, and efficient, and can be manufactured very cheap in comparison to other spring-saddles in the market.

75

The pins or studs herein described are preferably formed of india-rubber, so that when the springs are compressed the pins or studs will be compressed likewise, and thus form an additional elastic means.

80

I am aware that a spring-seat for saddles has been constructed of a series of spiral springs connected together at the top, and having metallic base-supports for said springs secured to a leather bottom; but this is simply a spring-seat which is secured to the saddle-tree. I am also aware that a saddle-tree has been provided with a groove in which is fitted a series of springs, a top plate being arranged to depress said springs; and I am also aware that a series 85 of elliptical springs have been connected at each end to bars extending across the saddle-tree; but I am not aware that a saddle-tree has been provided with a groove in which is fitted a plate, said plate having a series of pins 90 or studs extending upward, as shown, a series of springs being arranged to fit over the studs, so as to inclose them, and a top plate covering the springs, arranged substantially as shown.

95

What I claim as my invention is—

100

1. In a spring-saddle, a plate or plates secured to the cantle, pins or studs projecting

up from said plates, and springs fitting loosely over said pins, as set forth.

2. In a spring-saddle, the combination of the saddle-tree provided with grooves or recesses in the cantle, with plates fitting within said grooves, pins or studs projecting up from said plates, springs fitting loosely over said pins, and a plate covering the whole, as set forth.

10 3. In a spring-saddle, loosely-fitting springs

connected to the cantle of a saddle-tree, said springs fitting over india-rubber pins or studs projecting from the cantle, as set forth.

In testimony that I claim the foregoing as my own I have hereto affixed my signature 15 in presence of two witnesses.

MARTAIN LUTHER TOLBERT.
